United States Patent Office

Des. 195,624
Patented July 9, 1963

195,624

PRINTING MACHINE

Walter Behr and Helmut Keitel, Wilhelmshaven, Germany, assignors to Olympia Werke A.G., Wilhelmshaven, Germany

Filed Oct. 19, 1960, Ser. No. 62,541

Term of patent 14 years

(Cl. D26—5)

Fig. 1.

Fig. 3.

Fig. 2.

FIG. 1 is a front perspective view of a printing machine showing our new design;

FIG. 2 is another perspective view; and

FIG. 3 is a rear perspective view.

The essential features of the design reside in the portions shown in full lines on the drawing.

We claim:

The ornamental design for a printing machine, as shown and described.
